UNITED STATES PATENT OFFICE.

RUSSELL DEAN BELDEN, OF MARION, OHIO.

DESIGN FOR A TIRE-CASING.

57,491.

Specification for Design. Patented Apr. 12, 1921.

Application filed September 3, 1920. Serial No. 408,030. Term of patent 3½ years.

To all whom it may concern:

Be it known that I, RUSSELL DEAN BELDEN, a citizen of the United States, residing at Marion, in the county of Marion and State of Ohio, have invented a certain new, original, and ornamental Design for Tire-Casings, of which the following is a specification, reference being had to the accompanying drawings, forming a part thereof.

In the drawings,

Figure 1 is a perspective view of a fragment of a tire casing showing my new design, and

Fig. 2 is a plan view thereof.

I claim:

The ornamental design for a tire casing, as shown.

In testimony whereof I affix my signature.

RUSSELL DEAN BELDEN.
